UNITED STATES PATENT OFFICE.

JENNIE LEE GARCELON, OF CHICAGO, ILLINOIS.

DRESS-MAKER'S FITTING APPARATUS.

SPECIFICATION forming part of Letters Patent No. 439,500, dated October 28, 1890.

Application filed September 5, 1888. Serial No. 284,636. (No model.)

To all whom it may concern:

Be it known that I, JENNIE LEE GARCELON, of Chicago, in the county of Cook and State of Illinois, have invented a new and Improved 5 Dress-Maker's Fitting Apparatus, of which the following is a full, clear, and exact description.

This invention relates to a device to be used by dress-makers for obtaining the shape of a 10 person for whom a garment is to be cut out and made.

The object of the invention is to obviate the difficulties of dress-fitting, to enable an inexperienced person to obtain a perfect fit of any 15 form, to avoid the continual trying-on of the garment being made, to quickly and easily obtain an accurate fit, and to reduce the cost occasioned by fitting done by experienced dress-makers.

20 The invention consists in a harness-like apparatus to be applied to the figure of a woman and adjusted to the shape, which apparatus is constructed and arranged as hereinafter described and claimed.

25 Reference is to be had to the accompanying drawings, forming a part of this specification, in which similar figures of reference indicate corresponding parts in both the views.

Figure 1 is a view of the front of the invention, illustrating its use; and Fig. 2 is a 30 view thereof from the rear.

The fitting apparatus consists of a harness-like arrangement of a number of horizontal straps and vertical bands, as here shown, in 35 the form of a waist, extending from the throat to below the waist. The vertical bands 1, by means of which the apparatus may be opened at front or rear, are secured at their upper ends to a collar-strap 2 and are connected together from top to bottom by hooks and eyes 3. The vertical bands 4 in front are 40 connected at their upper end by buckles 5 to slitted shoulder-straps 6, connected by hooks and eyes 3 and secured at one end to the collar-strap 2 and at the other by buckles 5 to the arm-straps 7. The upper portion of vertical bands 4 is connected to horizontal straps 8, secured at one end to the front vertical bands 1 and at the other end connected 45 by buckles 5 to the arm-straps 7. The remaining portion of vertical bands 4 is slit, as at 8', and connected by hooks and eyes 3. The

slit portions of bands 4 are connected together and to front vertical bands 1 by horizontal straps 9 and buckles 5. The rear portion of the apparatus is constructed with vertical slit bands 10, fastened together by hooks and eyes 3, similarly to bands 4, and said bands are secured at their upper end to the arm-straps 7 and connected together and to rear vertical bands by means of horizontal straps 9 and buckles 5. Horizontal straps 9 also extend across the shoulders at the back, having one end secured to rear vertical bands 1 and the other end connected to arm-straps 65 7 by buckles 5. The bands 1 and slitted bands 4 10 are practically double bands, forming flaps, which may be disconnected and raised up to obtain access to the cloth in cutting. 70

By means of an apparatus constructed as above described, and having the shape and outline of a waist extending from the throat below the waist and the several parts adjustable by means of the straps 9 and buckles 5, 75 a perfect fit may be obtained and transferred to or duplicated in the garment to be cut out.

By means of the hooks and eyes the apparatus may be opened and its parts laid separately on the cloth in cutting the garment, and by this means, if there be inequalities in the sides of the person fitted, the inequalities may be copied. It is assumed that in employing the apparatus the person obtaining the duplicate of the form she wishes 85 to fit has sufficient judgment to have charge of the cutting. This being the case, no experience and skill in fitting is necessary other than a simple explanation of the adjustment of the apparatus. In this way women may 90 fit and make their own garments without knowing any rule of cutting or even one of the measurements of the garment to be made. There is no chance of making mistakes in cutting. In the case of prominent shoulder-blades or unequal hips, the apparatus will 95 note and provide for the irregularities of form. If the person to be fitted has on a stylishly-cut garment, the cut as well as the fit can be copied. 100

Apparatus to obtain duplicate fits of skirts and sleeves may be constructed on the same principle.

The invention broadly comprehends an ap-

paratus of this character by means of which a duplicate fit may be obtained from the form of a woman for whom a garment is to be made and the garment accurately cut out 5 without measurements, patterns, and fittings.

Having thus described my invention, what I claim as new, and desire to secure by Letters Patent, is—

1. A dress-maker's fitting apparatus, consisting of a neck-strap, arm-straps, shoulder-straps, front and rear main vertical bands connected to the neck-strap and detachably connected together, front, rear, and side slitted vertical bands, the portions of the slitted bands being detachably connected together, and adjustable horizontal bands connected to the vertical bands and arm-straps, substantially as described.

2. A dress-maker's fitting apparatus, consisting of the collar-strap 2, vertical front 20 and rear bands 1, connected together by hooks and eyes, slitted shoulder-straps 6, arm-straps 7, vertical front and rear and side slitted bands 4 and 10, some of them secured to the collar-straps and others to the arm-straps, the 25 portions of the said slitted straps 3, 4, and 10 being connected together by hooks and eyes, and horizontal straps 8 and 9, secured to the bands 1 and connected to the arm-straps and to the vertical slitted straps by buckles, substantially as herein shown and described.

JENNIE LEE GARCELON.
